UNITED STATES PATENT OFFICE.

ANTON VON KERPELY, OF VIENNA, AUSTRIA-HUNGARY.

GAS-PRODUCER.

1,114,072.

Specification of Letters Patent. Patented Oct. 20, 1914.

Application filed October 11, 1911. Serial No. 654,156.

To all whom it may concern:

Be it known that I, ANTON VON KERPELY, a subject of the King of Hungary, residing at Vienna, Austria-Hungary, have invented 5 certain new and useful Improvements in Gas-Producers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to rotary grate gas producers of that kind in which a rotating pan arranged at the bottom of a stationary shaft carries the grate which rotates with the pan and is formed with blow holes for 20 the air. The rotary pan is usually provided with a water seal for "sealing" the shaft, that is to say, for preventing the gas generated and the air blown in from escaping at the bottom of the shaft, though the 25 ashes may without difficulty be discharged through the water. These known arrangements give an excellent effect when pressures are used which do not greatly exceed the atmospheric pressure, but if higher 30 pressures are to be used in producers, the water seal arrangements hitherto used prove insufficient, especially with respect to the ash discharge. This will be readily conceived from the fact that the pan must have 35 a considerable height as the water on the outside will rise to a point corresponding to the pressure within the shaft. Of course a pan of that kind renders a continuous 40 discharge of the ashes very difficult or even impossible, the discharge of the ashes out of the pan requiring a reduction of the pressure and thereby decreasing the output 45 of the producer and interfering with its regular and efficient working.

45 In other known arrangements used previously to the before-mentioned arrangements the shaft terminates in a closed chamber in alignment with it into which the ashes are directly discharged and from 50 which they are removed from time to time through an opening controlled by a door or flap, a rotary plate being arranged within such chamber below the shaft. Such arrangements however, present the well known serious disadvantages which led to 55 the construction of rotary ash pans for dis-

charging the ashes, the chamber beneath the shaft being filled very rapidly, and thus no complete combustion of the fuel taking place, when no special means are provided for preventing this rapid descent of the fuel. Moreover the means usually provided for the purpose, namely the provision of a deep bed of non-combustible material under the fuel or the like, have not proved very effective.

Now this invention has for its object to remove the difficulties arising in connection with the high pressure blast, without altering the mode of discharging the ashes used in water seal arrangements, in which the ashes have to pass underneath the shaft through the rotating pan in which they accumulate on the outside being discharged continuously from it over its outer upper edge by means of an abutment surface or plate and a conveying scoop.

According to this invention the water is dispensed with, the rotary pan being housed in an annular air-tight chamber surrounding the lower end of the shaft and in closed connection therewith which prevents the communication with the outer atmosphere, this chamber being filled with air or gas of exactly the same pressure as that of the air blown in by the grate. The discharge of the ashes out of the shaft is thereby left unaltered, being continuously effected from the producer into a discharge chamber provided adjacent the shaft at the point of discharge which for the purpose of discharging the ashes from itself is adapted to be placed temporarily in communication with an ash pit through an ash passage provided at the point of discharge, and adapted to be closed in an air-tight manner. A further advantage in enabling a water seal to be dispensed with is that the gases generated in the producer are not liable to be impaired by becoming charged with water vapor.

One arrangement of apparatus embodying the invention is illustrated in the accompanying drawing by way of example.

The figure is a section representing the lower part of a gas producer.

a_1 is the tower shaped grate in the top of which a large number of very narrow tapering air apertures a_2 are formed. Through these numerous apertures of small sectional area the necessary amount of air for combustion, divided up into very fine jets, is

discharged at suitable pressure through the column formed by the charge. This results in a thorough and uniform distribution of the air for combustion throughout the entire 5 cross sectional area of the column of fuel in the producer shaft *c*, thereby insuring well regulated working and preventing the formation of detrimental blast ducts or air passages, as well as preventing over blowing 10 of the producer even where high pressure blast is used and the work is being forced. The grate *a* is carried by a rotary pan *b* and extends up into the producer shaft in the usual manner. The lower end of the 15 shaft is situated above the bottom of the pan and the rim or outer edge of the latter surrounds the shaft and extends to a zone above the zone of the lower end of the shaft. The sealing of the shaft is effected 20 by means of a sheet iron casing *d* which forms an annular gas tight chamber *e* surrounding the pan *b* and the shaft, and is in fixed and gas tight connection with the shaft. This annular chamber is connected 25 to the discharge chamber *f* proper, which is preferably formed by a suitable extension of said annular chamber and in permanent connection therewith. At the bottom of this extension *f* of the chamber *e* is an ash 30 passage *g*. The ashes are delivered over an inclined surface or chute *h* by means of ash-discharging apparatus comprising a collecting abutment surface or plate *h* and conveying scoop *i*. The chute *h* leads the ashes 35 into the ash passage *g*, the upper end of which is adapted to be closed in an air-tight manner by a slide *l* and the lower end of which communicates with a collecting chamber or ash-pit *n* adapted to be closed 40 in an air-tight manner at the outer end by a door or flap *m*. In this way the ashes accumulating above the retaining or closing slide *l* may be from time to time discharged into the air-tight ash-pit by opening such 45 retaining slide without reducing the pressure of the blast in the producer shaft and interfering with the proper working of the producer. Upon the ash passage being closed the ash-pit can be opened and the 50 accumulated ashes removed.

Claims:

1. A gas producer comprising a stationary shaft, a grate therein, a rotary ash-pan carrying said grate and surrounding the lower end of the shaft, sealing means for the shaft, 55 consisting of an annular gas tight chamber in fixed connection with the shaft surrounding the lower end of the same and the rotatable pan and having a gas tight joint with the latter, means for discharging ashes 60 automatically over the outer edge of the ash pan, said discharge depending upon the rotation of said pan, a gas tight ash discharging chamber at the discharge point of the ashes in connection with the annular gas 65 tight chamber, and means for withdrawing the ashes from the said discharging chamber.

2. A gas producer comprising a stationary shaft, a grate therein, a rotary ash pan carrying said grate, and surrounding the lower 70 end of the shaft, sealing means for the shaft, consisting of an annular gas tight chamber in fixed connection with the shaft surrounding the lower end of the same and the rotary pan and having a gas tight joint with 75 the latter, means for discharging the ashes automatically over the outer edge of the ash pan, said discharge depending upon the speed of rotation of said pan, a gas tight ash discharging chamber at the discharge 80 point of the ashes in connection with the annular gas tight chamber, a gas-tight collecting chamber capable of being alternately put into communication with the ash discharge chamber and the exterior, an abutment plate for discharging the ashes accumulated 85 in the pan over the upper edge of the latter, a chute leading from said upper edge to the collecting chamber, and a side plate for alternately establishing and shutting off 90 the communication with said collecting chamber.

In testimony that I claim the foregoing as my invention, I have signed my name in presence of two subscribing witnesses.

ANTON VON KERPELY.
